T. WATSON

ATTACHMENT TO SOUND REPRODUCING MACHINES FOR RECORD CLEANING

Filed Jan. 26, 1926

THEODORE WATSON

INVENTOR;

By *O. H. French*
his Attorney.

UNITED STATES PATENT OFFICE.

THEODORE WATSON, OF EAST MELBOURNE, AUSTRALIA, ASSIGNOR TO WATSONIA ENGINEERING AND MANUFACTURING COMPANY PROPRIETARY LIMITED, OF MELBOURNE, AUSTRALIA, A CORPORATION OF VICTORIA.

ATTACHMENT TO SOUND-REPRODUCING MACHINES FOR RECORD CLEANING.

Application filed January 26, 1926, Serial No. 83,794, and in Australia February 7, 1925.

My invention relates to an attachment for use with sound reproducing machines, and having means to bear upon the record surface to clean the grooves as the record rotates, preventing fine particles of loose matter being left in the grooves, the needle then not having the grinding damaging effect that it would have if the grooves were not cleaned, especially when the needle point becomes worn. Brushes are now sometimes attached to sound reproducing means for the aforesaid purpose, but they are accompanied by disadvantages which my invention avoids.

In the accompanying drawings Figure 1 shows part of a record adapted to rotate in the direction indicated by an arrow, and adjacent portions of a talking machine are shown, including a sound box fitted with a brush and a needle. The brush cleans the grooves before the latter reach the needle, which thus operates to the best advantage.

Figure 2 is a perspective view of my attachment, a part of a nut being broken away to exhibit a screw thread.

Figure 3 is a perspective view of an adjustable jaw of my attachment.

Figure 4 is an elevation of the brush front, and of the attachment by which the brush is carried.

Figure 5 shows the attachment modified, the brush being on an adjustable resilient arm.

Figure 6 is a sectional end view of the construction taken on lines 6-6 of Figure 5.

Figure 7 shows diagrammatically a plan of a fragment of a record, and shows the positions of the needle point and of my brush relatively to each other at the beginning of the record groove and at the end thereof, the effectiveness of the brush being maintained throughout.

"Brush" means in this specification a frictional sweeping element for cleaning the grooved record.

My attachment can be applied to rims of sound boxes of various forms. This has advantages compared with the goose-neck attachment, but my attachment is also adjustable relatively to the record.

To form my attachment, a frame 1 is made of bent metal or wire by producing a loop 2 near one end to form a fixed jaw, op-

posite to an adjustable jaw 3 which can be set by rotating a nut 4 the thread of which engages a screwthread 4^a upon one of the terminals of the frame. This adjustable jaw 3 is not rotatable, but is slideable, and may have slight looseness or play. It has a hole 3^a through which extends a correspondingly shaped part of the said terminal 1^a. This jaw has a lug 3^b extending longitudinally of the frame, as in Figures 2 and 5, and as part 3^b of the jaw is channelled at 3^c part of the limb 1^a fits therein.

1^b is a frame bend leading to the frame terminal 1^c, which is shown as a straight limb carrying means of attaching an adjustable clip 5 which has a recess as a housing for the head 6^a of a brush 6. I employ brushes having heads which slide into or out of the clip easily endwise, (see Figures 2 and 4).

The clip 5 has free springy flanges 5^a extending towards one another at their lower edges, but by insertion of the brush head 75 these flanges are pressed slightly apart, and provide the necessary firm grip. To mount the clip slidably, relatively to terminal limb 1^c, it is connected to a ferrule 5^b which is slideable along limb 1^c. The clip and ferrule 80 are either close together (as in Figures 1, 2, and 4) or are spaced apart—as in Figures 5 and 6, in which 5^a is a spring arm. The latter arm enables brush 6 to bear resiliently on the record, and to automatically compensate 85 for difference of height due to the fact that the needles used vary materially in length. Therefore this power of compensation is of value.

A is a needle, B the stylus bar, C the sound box, and D is the first groove of the record to be played. In Figure 7, A^x is the needle at the inner part of the grooved surface of the record, and 6^x is the brush at that part, D^x being the inner groove.

It is desirable to locate the needle as shown in Figure 1 before attaching the frame originally to the edge of the sound box, above the record with the said edge between jaws 2 and 3, the frame extending inwardly and somewhat downwardly.

I adjust spring clip 5 by means of a connection to the terminal, with the brush in contact with the record, and vertical or

oblique, as the user desires. The brush is wide and is made to bear on the record surface, at, and both inward and outward of, whatever groove of the record the needle 5 engages, so that the groove meeting the needle will always be clean. The brush at first extends a greater distance inwardly (see Figure 7) than outwardly. Each groove becomes repeatedly brushed before 10 it is rotated under the needle.

What I claim is:—

1. In a record cleaning attachment for phonograph reproducers, a brush carrying frame having a fixed jaw and an adjustable jaw loosely carried by a portion of the fixed jaw and projecting to embrace over the peripheral wall and against opposite faces of the reproducer, and a brush mounted on the frame and adjustable thereon in a direction parallel to the axis of the reproducer and transversely of the grooves of the records.

2. In a record cleaning attachment for phonograph reproducers, a brush carrying frame having a fixed jaw and an adjustable jaw loosely carried by the fixed jaw and projecting to embrace over the peripheral wall and against opposite faces of the reproducer, said adjustable jaw having its engaging surface concave, the edges thereof operating to grip the surface of the reproducer, and a brush mounted on the frame and adjustable thereon in a direction parallel to the axis of the reproducer and about the frame as a center.

3. In a clamping arrangement for a record cleaning device on phonograph reproducers, a fixed jaw having a threaded projection disposed parallel to the axis of the reproducer, an adjustable clamping jaw operating over said projection, and means operating over the threaded projection and against the adjustable clamping jaw.

4. In a record cleaning attachment for phonograph reproducers, a brush carrying frame comprising a wire bent upon itself to form a U-shaped member, one arm thereof having an offset portion to form a jaw midway of its length operating to engage 50 against the back face of the reproducer, the end of the wire beyond the jaw being partially threaded and disposed parallel to the axis of the reproducer, a second jaw adjust-

able over the threaded end portion of the wire and against the front face of the reproducer, and a nut operating over the threaded end and against the second jaw.

5. A brush carrying frame, as claimed in claim 4, in which the partially threaded end of the wire is flattened between the threads 60 and the offset portion, and the second jaw comprises an L-shaped member having one arm concave to bring the edges against the surface of the reproducer along radiating lines of the latter and the other arm U-shaped to embrace the flattened section of wire and prevent turning of the jaw.

6. In a record cleaning attachment for phonograph reproducers, a brush carrying frame having one end clamped to the reproducer and the other end projecting parallel to the axis of the reproducer and radially of the record, and a brush adjustable over said last mentioned frame end from a point in the path of the reproducer needle 70 and then transversely of the grooves of the record towards the center thereof.

7. A record cleaner attachment to be clamped to phonograph reproducers, comprising a wire frame threaded at one end 80 and projecting in a straight line a distance substantially greater than the intended clamping capacity of the attachment, the wire being then turned upon itself to form a loop to engage the rear face of the reproducer, the wire projecting straight again from the loop in a line substantially parallel with the axis of the reproducer and then curving back on itself in a straight portion parallel to the other straight portion, a jaw 90 adjustable over the threaded end of the wire and relative to the loop to engage the opposite side of the reproducer, a screw adjustable over the threaded end of the wire and against the jaw, a brush holder arranged on the other straight end of the wire and comprising an inverted U-shaped holder having a bracket movable about the wire and provided with a set screw adapted to engage the wire, and a brush having a 100 top portion slidably engaged in the U-shaped holder.

In witness whereof I have hereunto set my hand.

THEODORE WATSON.
